Primary Examiner — Rebecca Tsehay(74) Attorney, Agent, or Firm — BROOKS KUSHMAN
PC; John E. Nemazi(57) **CLAIM**The ornamental design for a cigarette rolling machine, as
shown and described.**DESCRIPTION**FIG. 1 is a perspective view of our cigarette rolling machine
showing our new design;

FIG. 2 is a right-side elevational view of FIG. 1;

FIG. 3 is a left-side elevational view of FIG. 1;

FIG. 4 is a top plan view of FIG. 1;

FIG. 5 is a bottom plan view FIG. 1;

FIG. 6 is a front side elevational view FIG. 1; and,

FIG. 7 is a rear side elevational perspective view FIG. 1.
The broken lines in the drawings depict portions of the
cigarette rolling machine that form no part of the claimed
design.**1 Claim, 2 Drawing Sheets**FIG. 1
